DESIGN FOR A GOLF DRESS

Fern E. Johnson, New York, N. Y.

Application November 7, 1939, Serial No. 88,090

Term of patent 3½ years

To all whom it may concern:

Be it known that I, Fern E. Johnson, a citizen of the United States, residing in New York city, in the county of New York and State of New York, have invented a new, original, and ornamental Design for a Golf Dress, of which the following is a specification, reference being had to the accompanying drawing, forming part thereof.

Fig. 1 is a front view of a golf dress showing my design.

Fig. 2 is the rear view thereof, and

Fig. 3 is a fragmentary view of the dress shown in Fig. 1 illustrating the collar in open position.

I claim:

The ornamental design for a golf dress, substantially as shown.

FERN E. JOHNSON.
